BOTTLE WASHER

Archie E. Ladewig, Waukesha, Wis., assignor to Archie Ladewig Co., Waukesha, Wis., a corporation of Wisconsin

Application March 7, 1955, Serial No. 492,501

16 Claims. (Cl. 134—74)

This invention relates in general to improvements in the art of placing receptacles in clean and sanitary condition preparatory to filling them with fluent commodity, and relates more particularly to improvements in the construction and operation of mechanism for automatically washing and rinsing bottles or the like.

The principal object of the present invention is to provide a relatively simple and compact automatic bottle washer of large capacity which is highly effective and reliable in operation.

Some of the more important specific objects of the invention are as follows:

To provide a bottle washing machine wherein the dirty bottles are supplied en masse in upright condition at one end of the unit and are automatically unscrambled and subsequently subjected to thorough washing and rinsing within an enclosure from which the clean bottles are ultimately discharged at the same end of the unit to which the dirty bottles are introduced.

To provide improved mechanism for unscrambling upright bottles being supplied en masse to a bottle washer and which may be utilized to effectively pre-arrange and to deliver to the internal bottle transporting conveyor of the machine, bottles having widely different diameters.

To provide a bottle washing unit in which a single attendant can control the mechanisms for supplying and transporting the bottles through and for discharging the clean bottles from the machine, and for circulating and delivering the washing and rinsing liquids against the bottles being thus transferred to, through and from the washer.

To provide a bottle washer of the type wherein an advancing series of bottles is subjected to successive pre-rinsing, soaking, washing, and final rinsing operations by liquids having progressively increasing and subsequently diminishing temperature, in order to eliminate bottle breakage.

To provide a bottle cleansing assemblage which utilizes caustic or other chemical as a cleansing agent and wherein undesirable waste of such valuable chemical is minimized.

To provide a bottle washing assembly involving the use of chemical solutions and clean water for treating a succession of bottles in successive segregated zones, and in which accumulation of the chemical within the bottom cavities of inverted bottles being transferred from the chemical zone, is prevented from being deposited in the clean water washing zone.

To provide an improved liquid type bottle cleanser in which the cleansing liquid is utilized most economically, while the mechanism for advancing the bottles and for circulating the liquid may be stopped at will and restarted with the cleansing liquid in proper condition for most efficient immediate use even after periods of considerable inactivity of the unit.

To provide a bottle washer in which undesirable foaming of the circulating cleansing liquid is constantly eliminated.

2

inated, and wherein the soaking and washing liquids are maintained in relatively clear condition for prolonged periods.

To provide an improved bottle washing machine wherein all parts are normally well concealed and protected, but are visible for inspection while the mechanism is operating, and are also readily accessible for removal of abnormal or accidentally jammed or broken bottles.

To provide a rapidly and effectively functioning bottle washing unit which requires minimum attention and is cooperable with various types of bottles to thoroughly wash and sterilize the same at minimum cost.

To provide a totally automatic and exceedingly compact bottle washer which may be installed and safely operated within limited space without subjecting the bottles to breakage due to impact or sudden variations in temperature, and which is adapted to handle bottles of diverse sizes and shapes.

These and other still more specific objects and advantages of the invention will be apparent from the following detailed description.

A clear conception of the various features constituting the present improvement and of the construction and operation of a typical bottle washer embodying the invention, may be had by referring to the drawings accompanying and forming a part of this specification wherein like reference characters designate the same or similar parts in the various views.

Fig. 1 is a side elevation of the bottle loading and unloading end of a commercial bottle washing unit embodying the present invention;

Fig. 2 is a longitudinal vertical section through the main soaking basin and through the successive washing and rinsing zones of the unit located above the soaking basin, this sectional view being a continuation of the portion of the machine illustrated in Fig. 1 and being drawn to the same scale;

Fig. 3 is a transverse vertical section through the same washing unit, taken along the line 3—3 of Fig. 2;

Fig. 4 is another transverse vertical section through the bottle washing unit, taken along the line 4—4 of Fig. 2;

Fig. 5 is an electrical diagram showing the electric circuits for controlling the functioning of the electrically actuated parts of the washing unit; and

Fig. 6 is an enlarged fragmentary and part sectional top view of the unscrambling partitions and accessories for enabling these partitions to cooperate with bottles of relatively small diameters.

While the invention has been illustrated and described as being embodied in an electrically driven bottle washer having successive transverse rows of bottle carrier pockets intermittently advanceable by an endless conveyor chain, and especially adapted to cooperate with small necked beverage bottles, it is not desired or intended to unnecessarily limit the scope or utility of the various improvements to such a structure; and it is also contemplated that specific descriptive terms employed herein be given the broadest possible interpretation consistent with the disclosure.

Referring to the drawing, the automatic bottle washing unit illustrated therein comprises in general, an elongated casing 8 having lower and upper bottle loading and discharge zones 9, 10 respectively at one end, and being provided internally with a lower soaking basin 11 and with a succession of washing and cleansing zones 12, 13, 14, 15 disposed above and separated from the basin 11 by a transverse partition 16; an endless chain conveyor 17 having a series of transverse rows of bottles carrying pockets 18 mounted thereon for advancing bottles 19 in succession while in upright position through

the soaking basin 11 and while inverted through the successive washing and cleansing zones 12, 13, 14, 15; mechanism for feeding the dirty bottles 19 toward and into the carrier pockets 18, for advancing the bottle laden conveyor along a definite path within the casing, and for delivering the clean bottles 19 from the pockets 18; and means for constantly circulating the cleansing fluids and for subjecting the bottles 19 thereto.

The main elongated housing or casing 8 may be formed of durable sheet metal being provided with removable accesses and inspection plates 21 at the sides thereof, and the transverse partition 16 is inclined toward one side of the casing 8 and is provided with upright end walls 22, 23 and with an intermediate wall 24 segregating the initial washing zones 12, 13 from the final cleansing zones 14, 15, see Figs. 2, 3 and 4. Located at one side of the casing 8 near the chemical solution washing zones 12, 13, is a housing 25 having therein a transverse division plate 26 forming an upper chemical solution defoaming space 27 which communicates with the zones 12, 13 above the partition 16 through an opening 28, and also forming a lower chamber 29 communicating with the basin 11 below the liquid level therein through another opening 30. Located at the opposite side of the casing 8 near the water cleansing zones 14, 15 is another housing 31 having therein a transverse division plate 32 forming an upper space 33 provided with a liquid inlet pipe 34 and which communicates with the liquid basin 11 through an opening 35, and also forming a lower chamber 36 communicating with the inlet 37 of a motor driven circulating pump 38. Each of the division plates 26, 32 has one or more cylindrical filter units 39 removably associated with openings therein, and each of the housings 25, 31 may be provided with a closure cover 40.

The lower bottle loading zone 9 located at the front end of the casing 8 is provided with a continuously operable auxiliary endless chain conveyor 43 actuated by an electric motor 44 through an endless drive 45 coacting with a transverse drive shaft 46, as shown in Fig. 1, and the upper deck of this conveyor 43 is adapted to have the dirty bottles 19 deposited upon its forward upper desk portion en masse and in upright position but not in any definite pre-arrangement. Located above the rearward portion of this upper deck of the conveyor 43, is a series of laterally oscillatable parallel upright bottle unscrambling and row forming partitions 47 which are suspended from above by horizontal slides 48 and are reciprocable by means of an eccentric 49 driven by the motor 44 and which is connected by a rod 50 with an actuating shaft 51 having an eccentric portion coacting with the front slide 48, see Figs. 1 and 6. Directly beyond the rear edges of the movable partitions 47 is a like series of stationary partitions 52 which are fixedly suspended from above by a supporting plate 53 and the lower portion of the opposite sides of each of which is provided with an arcuate rigid guide member 54.

The partitions 47, 52 are spaced apart uniform distances of sufficient width to permit passage therebetween of bottles 19 having maximum diameter, but in order to enable the unscrambling partitions 47 to accommodate bottles 19 of smaller diameter, the mid portions of these movable partitions 47 may be provided with removable guides 55 such as shown in Fig. 6. Each of the intermediate guides 55 has a tapered front end 56 and a central slot 57 in its upper wall which is adapted to be slid along one of the partitions 47 and to rest upon narrow ledges 58 protruding from the opposite sides of the adjacent partition, and each of these guides also carries a transverse pin 59 at its opposite end adapted to be inserted through an angular retaining opening formed in the partition 47. The opposite side guides 55' are approximately one-half the width of the intermediate guides 55 and may be detachably suspended from the extreme opposite side partitions 47 by means of screws 60.

as illustrated in Fig. 6, but when the guides 55, 55' are applied to the movable partitions 47 the guide members 54 need not be altered since they are of sufficient width to coat with bottles 19 of any diameter within the limits of the dimensions of the carrier pockets 18.

The bottle feeding mechanism located near the lower loading zone 9 of the unit, also embodies an oscillatory bottle tilting element 62 mounted upon a transverse shaft 63 provided with an end pinion 64 which is co-operable with a reciprocating rack 65, as depicted in Fig. 1. The element 62 is composed of a series of quadrants adapted to swing upwardly between the arcuate guide members 54 of the fixed partitions 52 and to engage the bottoms of the successive dirty bottles 19 so as to advance and tilt these bottles and deposit them upon a transverse tiltable serrated guiding shelf 66. The rack 65 is reciprocable by an arm 67 connected to a lever 68 which is oscillatable about a pivot 69 and this lever 68 is connected by links and levers 70, 71, 72, 73 to a rotary cam 74 mounted upon a transverse shaft 75 journalled in bearings carried by the casing 8 and which is driven by the main driving motor 76. The shelf 66 is swingable downwardly about a pivot 77 by an arm 78 in order to present the dirty bottles to a pre-rinse zone 79 and a transverse pusher bar 80 which is guided for horizontal movement along the shelf 66 by slots 81 is movable back and forth by the upper swinging end of the lever 68 so as to push the successive rows of pre-rinsed bottles 19 off of the shelf 66 toward the adjacent horizontally disposed pockets 18 of the main conveyor after the shelf has been returned to horizontal position, following each pre-rinse operation.

The upper clean bottle unloading zone 10 which is also located at the front end of the machine above the loading zone and the bottle unscrambling mechanism, is provided with a transverse series of horizontally reciprocable ejectors 83 which are periodically movable along guideways 84 by means of a lever 85 secured to the pivot shaft 86' of the lever 71 and which is oscillatable by the same cam driven link 72 and lever 73 which oscillates the lever 71. These ejectors 83 are adapted to push the clean bottles 19 horizontally from within the successive rows of pockets 18 onto a bottle righting rack 86 which is swingable about a pivot 87 from horizontal into upright position, by means of an arm 88 and a connecting link 89 secured by a lever 90 to a transverse oscillatory shaft 91 which is also operatively connected to the pusher bar actuating lever 78 by an arm 92 and a connection 93. The shaft 91 is oscillatable by another arm 94 connected to an arm 95 which is swingable about the pivot shaft 96 by a link 97 and is operable by another cam 74 at the opposite end of the shaft 75, and the bottle righting rack 86 is swingable to deposit the finally cleansed bottles 19 in upright position upon a transverse endless bottle discharge conveyor 98, as illustrated in Fig. 1.

The main endless conveyor 17 is provided with rollers 100 which coat with fixed guideways 99 secured to the opposite side walls of the casing 8, in a well known manner, to cause the successive rows of bottles 19 confined within the carrier pockets 18 to intermittently advance in horizontal position along the opposite casing ends, in upright position through the chemical solution soaking basin 11, and in inverted position through the washing and cleansing zones 12, 13, 14, 15. The mechanism for thus advancing the main conveyor 18 is also shown in Fig. 1, and comprises a pair of levers 101 mounted upon a pivot 102 and carrying pawls which are co-operable with the rollers 100 of the main conveyor chain, the upper swinging ends of the levers 101 being eccentrically connected to the cam disks 74 mounted on the shaft 75 which is driven by the motor 76, by means of connecting rods 103 and pins 104. The motor 76 which is located midway between the cams 74 thus functions to drive both the bottle loading and unloading mechanisms as well as the main conveyor, and also actuates

the washing and cleansing liquid delivery devices confined within the zones 12, 13, 14, 15 in a manner to be explained later.

Located within the chemical solution basin 11 which extends throughout the major lower portion of the casing 8, is a steam coil 106 for heating the caustic bottle soaking solution, and disposed within the washing and cleansing zones 12, 13, 14, 15 are successive transverse rows of spray nozzles 107, 108, 109, 110 and spray pipes 111, 112 spaced from these nozzles sufficiently to permit the bottles 19 to be advanced between the pipes and the nozzles, see Figs. 2, 3 and 4. The transverse spray pipes are stationary, but all of the nozzles are mounted upon a vertically movable horizontally elongated support 113 which is suspended from the horizontal arms of bell cranks 114 by upright links 115, and these bell cranks 114 are swingable upon pivot shafts 116 and have their upstanding arms interconnected by a rod 117 embraced by a coil spring 118 one end of which coacts with a fixed abutment 119 while its opposite end engages nuts 120 adjustable along the rod 117 to vary the spring tension. This spring 118 counter-balances the weight of the support 113 and of the spray nozzles carried thereby, and the support 113 is movable by a lever 121 secured to the front pivot shaft 116 and which is connected to an arm 122 mounted on the main pivot shaft 96 by a connection 123, see Figs. 1 and 2.

The means for supplying, heating and circulating washing and cleansing liquid through the various bottle cleaning and rinsing zones of the bottle washer are illustrated in Figs. 1 to 4 inclusive, and consist primarily of the electric motor driven centrifugal pump 38 which receives its supply of chemical solution from the chamber 36 beyond the filter units 39 confined within the housing 31, and conduits and heaters through which the liquids are propelled by the pump 38. Fresh water is supplied to the bottle washing unit at city water pressure by a pipe 125 and a portion of this fresh water is delivered against the bottles 19 just prior to their exit from the machine through the nozzles 110 and the spray pipe 112 located in the final zone 15 in order to thoroughly rinse these bottles. The admission of fresh water to the cleansing spray nozzles 109 located in the zone 14 is controlled by a solenoid actuated valve 126 located in a pipe 127 which conducts the fresh water passing the valve 126 into one end of an elongated tube heater 127' located at one side of the casing 8 well above the level of the solution in the basin 11. In this heater 127' the fresh liquid flows through the tubes 128 while heated chemical solution from the basin 11 is circulated around the exteriors of these tubes 128 by the pump 38, and the pre-heated clean water is delivered from the opposite end of the main heater 127' through a pipe 129 and a heating coil 130 disposed beneath the initial washing zone 12, and is ultimately sprayed against the bottles 19 in the final cleansing zone 14 under city water pressure through the nozzles 109. In order to effect such spraying only when the nozzles 109, 110 have been elevated into active position, a whistle or signal valve 131 which is operable by a connection 132 secured to the rear bell crank 114 may be provided, as illustrated in Fig. 2, this valve being located in the fresh water supply pipe 125.

A portion of the hot chemical solution delivered through the discharge line 134 of the main pump 38 is forced through a strainer 135 and through one pipe 136 directly to the initial chemical solution spray nozzles 107 and pipes 111 located in the first washing zone 12, and thus subjects the successive bottles 19 to hot chemical solution sprays at substantially the same temperature as that of the solution in the soaking basin 11. However, another portion of the chemical solution discharged from the strainer 135 is delivered through a branch pipe 137 into one end of the main heater 127' and from the opposite end of this heater through piping 138 to the secondary spray nozzles 108 and pipe 111, thus extracting some

heat from the chemical solution passing through the heater and subjecting the successive bottles 19 to somewhat lower temperature in the zone 13 than that existing in the initial washing zone 12. Most of the spent chemical solution from the two washing zones 12, 13 drains down the inclined partition 16 and through the opening 28 and housing 25 into the basin 11, but the auxiliary heating coil 130 is disposed in the bottom of the initial washing zone 12 so that hot chemical solution dropping thereon will immediately heat the fresh liquid flowing through this coil whenever the unit is started.

The nozzles 107, 108, 109, 110 which are mounted upon the movable support 113 are all connected to their respective liquid supply pipes by flexible tubes as shown, and the washing and cleansing liquid to which the successive bottles 19 are subjected in the several zones 12, 13, 14, 15 is of gradually diminishing temperature advancing toward the front of the washer so that breakage of bottles due to sudden changes in temperature within the casing 8 is positively avoided. In order to initially heat the bottles 19 before they are admitted to the basin 11, the liquid which is delivered against these bottles in the pre-rinse zone 79 is preferably derived from the heat exchanger 127' through a pipe 141, as shown in Fig. 3 and the spent water discharged from the pre-rinse zone 79 may be drained away to the sewer. Also in order to eliminate loss of valuable chemical solution which accumulates in the recessed bottoms of the inverted bottles 19 being advanced from the zone 13 to the zone 14, the main endless conveyor 17 is caused to travel over a hump 140 on its guideway and which is located directly above the intermediate wall 24, and this hump 140 serves to tilt the inverted bottles rearwardly as illustrated in Fig. 2 thereby returning accumulated chemical solution to the zone 13. The improved bottle washer may be automatically operated with the aid of an electrical system such as shown in Fig. 5, with the aid of a single control switch 142 preferably disposed near the front end of the unit, and cooperates with the motors 76, 145 and with the solenoid valve 126 through relays 143, 144 and electric wiring 146 connected to a main line 147.

When the various parts of the improved unit have been constructed and assembled as hereinabove described, and the various linkages have been adjusted to produce proper functioning of the mechanism, the machine may be initially set in motion by manipulating the main control switch 142 thereby actuating the solenoid valve 126, the main driving motor 76 and the main pump propelling motor 145 for the liquid circulating pump 138. If the mechanism is all functioning properly, the motor 44 which drives the auxiliary bottle feeding conveyor 43 and which may also be utilized to drive the auxiliary bottle discharge conveyor 98, may be started whereupon the mechanical portion of the unit is ready for normal operation. The basin 11 should then be filled with chemical solution which should be heated to approximately 140° F. by admission of steam to the heating coil 106, and fresh water under pressure and at city water temperature should be admitted through the supply pipe 125; and while the cover 40 which is applied to the filter housing 31 need not be sealingly attached and may even be omitted, the other cover 40 which coacts with the defoaming housing 25 on the opposite side of the casing 8 must be sealingly applied and held in place when the washer is operating.

With the mechanism and the liquid supply and circulating devices thus placed in operating condition, the dirty bottles 19 may be deposited en masse and in upright condition upon the front portion of the upper deck of the feed conveyor 43 which promptly advances these bottles toward the laterally oscillating unscrambling partitions 47 disposed above the rear portion of this conveyor 43. These partitions 47 gradually separate the mass and arrange the dirty bottles in parallel rows extending longitudinally of the washer, and the constantly oscillating tilting elements 62 receive the rear end bottles of these

rows and advance them along the guides 54 between the fixed partitions 52 while simultaneously tilting the bottles 19 from upright into horizontal position and delivering them upon the shelf 66. This shelf 66 is periodically swung from horizontal to inclined position so as to expose the bottles resting thereon to the spray jets within the pre-rinse zone 79 and which receives pre-heated fresh water from the heat exchanger 127 through the pipe 141, thus giving all of the entering dirty bottles an initial rinse.

When the shelf 66 is again returned to horizontal position the pre-rinsed bottles 19 resting thereon are disposed rearwardly of the pusher bar 80 which is subsequently moved rearwardly to push the row of bottles horizontally into an adjacent row of horizontally disposed pockets 18 of the main conveyor 17, see Fig. 1.

While the dirty bottles 19 are thus being fed and subjected to pre-rinsing, the main conveyor 17 is being advanced step by step to cause the bottle laden pockets 18 to carry the admitted bottles 19 downwardly into and through the elongated soaking basin 11 in upright position, as shown in Fig. 2. After prolonged soaking of the bottles 19 both internally and externally within the basin 11, they are transported upwardly in horizontal position along the rear end wall of the casing 8 and are inverted and moved forwardly by the conveyor 17 in advance of the initial washing zone 12. The rows of inverted bottles 19 are thereafter transported step by step through the successive washing and rinsing zones 12, 13, 14, 15, and whenever they are moving forwardly the fresh water control valve 131 will shut off the fresh water supply; but whenever the bottle advancement ceases, the nozzle support 113 will be elevated to bring the nozzles 107, 108, 109, 110 into direct coaction with the bottle neck openings and the valve 131 will function to control the flow of fresh water from the heat exchanger 130 through the nozzles 109 and rear spray pipes 112, past the solenoid actuated valve 126, chemical solution will also be circulated by the pump 38 through the nozzles 107, 108 and spray pipes 111, thus insuring thorough washing and rinsing of all of the bottles passing through the successive cleansing zones 12, 13, 14, 15.

The chemical solution which drops from the inverted bottles 19 in the washing zones 12, 13 collects upon the inclined transverse partition 16 rearwardly of the wall 24 and drains into the upper space 27 within the housing 25 through the opening 28, and after passing through the filter units 39 this chemical solution is returned to the basin 11 through the chamber 29 and the opening 30. Other hot chemical solution is constantly withdrawn from the basin 11 through the lower chamber 36 of the other housing 31 past the filter units 39 and through the space 33 and opening 35, and is delivered by the main circulating pump 38 through the strainer 135 from the discharge end of which a portion of the chemical solution is re-circulated directly through the initial washing zone 12 while another portion is circulated through the heater 127' and from thence through the second washing zone 13. The fresh water admitted to the third cleansing zone 14 is first caused to flow through the heater 127' before being delivered against the bottles 19, thereby absorbing heat from the chemical solution which passes through the heater to the second zone 13 and heating the fresh water delivered to the third zone 14.

The temperatures of the liquid delivered against the bottles in the successive zones 12, 13, 14, 15 and assuming the temperature of the fresh water admitted to the washer to be approximately 50° F., will be approximately 140° F. in the first zone 12, 125° F. in the second zone 13, 85° in the third zone 14 and in the pre-rinse zone 79, and 50° in the final rinsing zone 15, thus constantly insuring gradual tempering and avoiding bottle breakage. In order to prevent delivery of cold fresh water against the bottles 19 in the fresh water cleansing zone 14 when the washer is stopped, the auxiliary heating coil 130 is

cated above the partition 16 beneath the initial zone 12 and through which the fresh liquid flows, is subjected to hot chemical solution whenever the machine is re-started, thus promptly warming this fresh water. Since the bottoms of the bottles 19 are recessed and accumulate quantities of chemical solution from the spray pipes 111 within the zones 12, 13, and in order to eliminate waste of this chemical solution, the successive rows of inverted bottles passing over the hump 140 from the zone 13 to the zone 14, will be tilted so as to spill the accumulated chemical solution back into the zone 13 rearwardly of the division wall 24.

The improved bottle washing unit is thus operable to automatically and effectively pre-arrange the dirty bottles 19 in successive rows at one end of the casing 8, to thoroughly soak and cleanse the bottles while proceeding through the basin 11 and the zones 12, 13, 14, 15, and to deliver them in clean condition from the same end of the casing 8 at which they are unscrambled and admitted to the washer. The successive bottles 19 are gently advanced and are subjected to gradual temperature changes throughout their entire treatment so that bottle breakage is reduced to a minimum, and the improved unscrambling device is adapted to cooperate effectively with bottles 19 of diverse shapes and diameters. While the bottle feeding conveyor 43 and the bottle unscrambler may be operated by a separate electric motor 44, the main conveyor 17 and the main liquid circulating pump 38 are driven by electric motors 76, 145 the operation of which is controlled by a common switch 142 thus enabling a single attendant to conveniently actuate the main washing unit.

The improved system for controlling and circulating the cleansing liquids besides eliminating waste of chemical solution by providing the hump 140 for the bottle conveyor 17, also enables the circulating pump 38 for the hot chemical solution to operate most effectively by eliminating foaming in the housing 25, and the provision of the filter units 39 and strainer 135 insures removal of foreign matter from the cleansing solution and maintains this liquid in clean condition at all times. The valve 131 coacts with the solenoid valve 126 to eliminate the waste of liquid when the bottles 19 are being advanced and the sprays are inactive, and all parts of the washer are well protected during normal operation while still being readily accessible for inspection and removal of abnormal bottles with minimum loss of time. The improved bottle washing machine has proven highly satisfactory and successful in commercial use, and has enormous capacity considering its compactness.

It should be understood that it is not desired to limit this invention to the exact details of construction and operation of the bottle washer herein specifically illustrated and described, for various modifications within the scope of the appended claims may occur to persons skilled in the art.

I claim:

1. In a bottle washer, a casing having therein means for dividing the casing into a lower chemical solution bottle soaking basin and a succession of upper chemical solution and fresh water bottle washing zones segregated from said basin, a conveyor for transporting bottles successively in upright position while immersed within chemical solution through said lower basin and in inverted position while subjected to washing sprays through said upper zones, means for heating the chemical solution in said basin, means for circulating a portion of the hot chemical solution from said basin directly through said chemical solution bottle washing zone, and means for pre-heating the water delivered to said fresh water bottle washing zone with another portion of the hot chemical solution passing through said circulating means.

2. In a bottle washer, a casing having therein a lower hot chemical solution bottle soaking basin and a succession of upper chemical solution and fresh water bottle

spraying zones, a main conveyor for transporting successive transverse rows of bottles in upright position through said basin and in inverted position successively through said chemical solution and fresh water spraying zones, a heat transfer device located above the liquid level in said basin, a pump for circulating a portion of the hot chemical solution from said basin directly through said device and another portion through said chemical solution spraying zone, and means for admitting fresh water to said fresh water bottle spraying zone through said device to pre-heat said water.

3. In a bottle washer, a casing having a hot chemical solution bottle soaking basin extending throughout its major lower portion and being provided above said basin with a series of bottle spray washing zones, the first two washing zones of said series having chemical solution bottle sprays therein and a subsequent washing zone of the series having fresh liquid sprays therein, a heat transfer device located above the level of the liquid in said basin, means for delivering some hot chemical solution from said basin directly to the first of said chemical solution bottle sprays and for simultaneously delivering other of said hot chemical solution through said device to the second chemical solution bottle sprays of said series, and means for conducting the fresh liquid to said fresh liquid bottle sprays through said device to pre-heat said fresh liquid.

4. In a bottle washer, a casing having a hot chemical solution bottle soaking basin extending throughout its major lower portion and being provided above said basin with a series of bottle spray washing zones segregated from the basin, the first two washing zones of said series having chemical solution bottle sprays therein and a subsequent washing zone of the series having fresh liquid sprays therein, a main heat transfer device located above the level of the liquid in said basin, means for circulating some hot chemical solution from said basin directly to the first of said chemical solution bottle sprays and for simultaneously delivering other of said hot chemical solution through said main device to the second chemical solution bottle sprays of said series, means for conducting the fresh liquid to said fresh liquid bottle sprays through said main device to preheat said fresh liquid, and an auxiliary heat transfer device below said first chemical solution washing zone for preheating the fresh liquid by heat derived from the spent hot chemical solution in said first zone.

5. In a bottle washer, a casing having therein a lower hot chemical solution bottle soaking basin and a series of bottle washing zones above said basin, means for conveying bottles in succession through said soaking basin and said washing zones, a main heat transfer device located above the liquid level in said basin, means for circulating hot chemical bottle washing solution from said basin through said device to an initial washing zone of said series, an auxiliary heat transfer device beneath said initial washing zone supplied with heat from spent liquid delivered from said zone, and means for supplying fresh bottle washing liquid to a subsequent washing zone of said series through said auxiliary heat transfer device to pre-heat said fresh liquid whenever the machine is started.

6. In a bottle washer, a casing having therein a lower chemical solution bottle soaking basin and an upper chemical solution bottle spray washing zone segregated from said basin, a conveyor for transporting successive bottles through said basin and said zone in succession, means for delivering hot chemical solution from said basin to said zone, and means including a laterally inclined partition spanning said basin and a solution clarifying device located externally of said casing near the lower end of said partition for returning the spent chemical solution from said zone to said basin.

7. In a bottle washer, a casing having therein a lower

chemical solution bottle soaking basin and an upper chemical solution bottle spray washing zone segregated from said basin, a conveyor for transporting successive bottles through said basin and said zone in succession, a strainer, a pump for delivering hot chemical solution from said basin through said strainer to said washing zone, and means including a filter for clarifying and returning the spent chemical solution from said zone to said basin.

8. In a bottle washer, a casing having therein a lower bottle soaking basin segregated from a series of upper bottle washing zones by a laterally inclined approximately horizontal partition, a conveyor for transporting successive bottles through said basin and said zones in succession, a pump for delivering hot chemical solution from said basin to an initial zone of said series, a liquid defoaming device, means for returning spent chemical solution from said initial zone to said basin through said device, and means for conducting spent washing liquid from the lower portion of said partition into said basin through said defoaming device.

9. In a bottle washer, a casing having therein a lower bottle soaking basin and a series of upper bottle washing zones segregated from the basin by a transverse partition, a conveyor for transporting successive bottles through said basin in upright position and through said zones in succession in inverted position, a filter on each side of said casing, a heat exchanger above said basin, a pump for delivering liquid from said basin directly to an initial zone of said series and through said heater to a subsequent zone, and means for returning spent washing liquid from said zones through said filters to said basin and said pump.

10. In a bottle washer, a casing having therein a lower bottle soaking basin and several upper bottle spray washing zones, a conveyor for transporting bottles successively through said basin and said zones, means for heating the liquid in said basin, a heat transfer device located above the level of the liquid in said basin, means for circulating hot liquid from said basin through said device to one of said zones, and means for conducting fresh liquid through said device to another of said zones, the hot liquid in said device being returnable by gravity to said basin when the machine is stopped.

11. In a bottle washer, a casing having a hot chemical solution bottle soaking basin in its lower portion and being provided above said basin with a series of bottle spray washing zones, the first two washing zones of said series having chemical solution bottle sprays therein and a subsequent washing zone of the series having fresh liquid sprays therein, a heat transfer device located between said zones and said basin, means for delivering some hot chemical solution from said basin directly to the first of said chemical solution bottle sprays and for also delivering other of said hot chemical solution through said device to the second chemical solution bottle sprays of said series, and means for conducting the fresh liquid to said fresh liquid bottle sprays through said device to pre-heat said fresh liquid.

12. In a bottle washer, a casing having therein a lower hot chemical solution bottle soaking basin and a series of bottle washing zones above said basin, means for conveying bottles in succession through said soaking basin and said washing zones, a main heat transfer device located between said zones and said basin, means for circulating hot chemical bottle washing solution from said basin through said device to an initial washing zone of said series, an auxiliary heat transfer device between said initial washing zone and said basin and being supplied with heat from spent liquid delivered from said zone, and means for supplying fresh bottle washing liquid to a subsequent washing zone of said series through said auxiliary heat transfer device to pre-heat said fresh liquid whenever the machine is started.

13. In a bottle washer, a casing therein a lower bottle

11

soaking basin and a series of upper bottle washing zones segregated from the basin by a transverse partition, a conveyor for transporting successive bottles through said basin in upright position and through said zones in succession in inverted position, a filter on each side of said casing, a heat exchanger between said zones and said basin, a pump for delivering liquid from said basin to an initial zone of said series and through said heater to a subsequent zone, and means for returning spent washing liquid from said zones through said filters to said pump.

14. In a bottle washer, a casing having therein a bottle soaking basin and several successive spray washing zones, means for heating the liquid in said basin, means for advancing bottles in succession through said basin and through the successive spray zones, a heater located above the liquid level in said basin, a pump for circulating a portion of the hot liquid from said basin directly through an initial spray zone and another portion of said hot liquid through said heater and a subsequent spray zone while the bottles are being spray washed, means for supplying relatively cool liquid to a further subsequent spray zone through said heater to heat said cool liquid, and a control valve in said cool liquid supply means operable to interrupt the cool liquid supply whenever the bottles are advancing from zone to zone.

15. In a bottle washer, a casing having therein a hot liquid bottle soaking basin and several sets of liquid delivery nozzles segregated from said basin, a conveyor for advancing successive bottles through said basin and past said nozzle sets in succession, a heat exchanger located adjacent to said basin, a pump for delivering a portion of said hot liquid from said basin directly to an initial set of said nozzles and another portion to a subsequent nozzle set through said heat exchanger, means for supplying cool water through said heat exchanger

12

to heat said cool water as it passes to a subsequent set of said nozzles, a valve in said cool water supply means operable automatically to interrupt the cool water supply whenever the washer stops, means operable when the washer is stopped and the flow of cool water is interrupted for also stopping said pump and the flow of hot liquid through said heat exchanger, and means for conducting hot liquid from said heat exchanger into said basin to prevent build up of temperature of the cool water during periods of inactivity of the washer.

16. In a bottle washer, a casing having therein a bottle soaking basin and several successive bottle spraying zones, means for advancing successive bottles through said basin and said spraying zones in succession, means for supplying hot liquid from said basin to an initial spraying zone, a heat exchanger disposed beneath said initial spraying zone and above said basin, means for supplying cool liquid through said heat exchanger to a subsequent spraying zone to heat said cool liquid, an electrically actuated control valve for interrupting the cool liquid supply whenever the washer stops, and means cooperable with said valve to stop the delivery of hot liquid to said initial spraying zone whenever the washer is stopped thereby preventing a build up of temperature of the liquid within said heat exchanger during periods of inactivity of the washer.
